Specification for Design.

Patented May 11, 1920.

Application filed August 21, 1919. Serial No. 319,038. Term of patent 7 years.

To all whom it may concern:

Be it known that I, HENRY KNOTT, a subject of Great Britain, residing at Boston, in the county of Suffolk and State of Massachusetts, have invented a new, original, and ornamental Design for a Spoon, Fork, or Similar Article, of which the following is a specification, reference being had to the accompanying drawings, forming a part thereof.

In said drawings—

Figure 1 is a front view of my design for spoons, forks or similar articles;

Fig. 2 is a back view of the same;

Fig. 3 is a cross sectional view of the same, taken at the line 3—3 on Fig. 2.

I claim:

The ornamental design for a spoon, fork, or similar article, as shown.

Boston, Mass., Aug. 16, 1919.

HENRY KNOTT.
